DESIGN FOR A TEXTILE FABRIC

William Rose, New York, N. Y.

Application April 15, 1936, Serial No. 62,124

Term of patent 3½ years

To all whom it may concern:

Be it known that I, William Rose, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure is a plan view of a textile fabric

showing my new design. A single unit of my design is substantially comprised within the area defined by the indicating lines shown on the drawing, which unit is repeated over the surface of the fabric in the relation indicated.

I claim:

The ornamental design for a textile fabric substantially as shown and described.

WILLIAM ROSE.
